UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPE-BAR GUIDE.

Application filed February 18, 1922. Serial No. 537,444.

To all whom it may concern:

Be it known that I, OTTO A. HOKANSON, a citizen of the United States, residing at Woodstock, in the county of McHenry and 5 State of Illinois, have invented certain new and useful Improvements in Type-Bar Guides, of which the following is a specification.

This invention relates to guide mechanism 10 for accurately directing the stroke of a type bar at the time that the bar engages the paper carried by the typewriter platen.

The invention has for its object the provision of a guide of the class named which 15 shall be of improved construction and operation, and which shall be readily and accurately adjustable.

The invention is exemplified in the combination and arrangement of parts shown 20 in the accompanying drawing and described in the following specification, and it is more particularly pointed out in the appended claims.

In the drawing—

25 Fig. 1 is a front elevation of a portion of a typewriter showing one embodiment of the present invention applied thereto;

Fig. 2 is a top plan view of the mechanism shown in Fig. 1;

30 Fig. 3 is a horizontal section on line 3—3 looking upwardly; and

Fig. 4 is a perspective view of a detail of construction.

In the drawing, the numeral 10 designates 35 a typewriter platen, and 11 designates a portion of a type bar segment positioned below and in front of the platen 10 and provided with a plurality of type bars 12 which swing upwardly and rearwardly to 40 strike the platen 10. Carried by the type bar segment 11 is a type bar guide supporting plate 13 having an opening 14 therein to permit the scale 15 to be visible, there being index points 17 and 18 to indicate the 45 writing position along the scale 15.

The plate 13 is provided with dowel pins 19 which project forwardly through the segment 11 and screws 20 extend through the segment 11 into the plate 13 to securely 50 hold the plate 13 in place. The plate 13 is provided with a pair of upwardly projecting bracket members 21 which carry forwardly projecting L-shaped supports 22.

Plates 23 are mounted on the upper hori-

zontal flanges of the supports 22 and are 55 held in place on the supports by screws 24 which project through slots 25 into threaded openings in the supports 22. Abutment guides 26 extend upwardly from the brackets 21 and engage the rear edges of the plates 60 23 to accurately position the plates 23 on their supports. The lateral edges of the plates 23 are provided with downwardly extending flanges 27 having slots 28 therein for engaging screws 29 threaded in the vertically extending portions of the supports 22. The flanges 27 are received in a groove between the heads of the screws 29 and circumferential flanges 30 formed on the screws 65 in spaced relation to the heads. 70

It will be apparent that rotation of the screws 29 will positively move the plates 23 for adjustment on their supports, the direction of movement depending upon the direction of rotation of the screws. The 75 inner edges of the plates 23 are provided with rearwardly converging curved flanges 31, the rear ends of which project between the brackets 21 and form stops for the outward movement of the plates 23 and their 80 guide flanges. It will be apparent that the plates 23 and their guide flanges 31 may be adjusted to vary the width of the opening between them and that they may both be adjusted either to the left or right to properly position the guide opening between them relative to the printing point of the type bars. These adjustments are accomplished without changing the angular position of the guide flanges relative to one another, or to the platen. Since the plates are 85 moved by threaded members, adjustments may be very accurately made and when completed the parts are firmly held in place 90 by the locking screw 24. 95

I claim:

1. A type bar guide comprising a support, a guide member mounted on said support, a threaded device for shifting said guide member in two directions of adjustment on said support, and a separate locking device for retaining said guide member in various adjusted positions. 100

2. A type bar guide comprising a pair of horizontally arranged plates having flange guides on adjacent edges thereof, a support for each of said plates, a threaded device for shifting each of said plates on its sup- 105

port, and a screw for locking each of said plates in various adjusted positions on its support.

3. A type bar guide comprising a pair of spaced supports, plates slidably mounted on said supports having flange guides on adjacent edges thereof, screws having circumferential grooves therein threaded in said supports, and flanges on said plates engaging said grooves for moving said plates when said screws are turned.

4. A type bar guide comprising a pair of spaced supports, plates slidably mounted on said supports and having spaced flange guides on adjacent edges thereof, screws threaded in said supports and engaging said plates for shifting said plates in opposite directions on their supports, and locking screws for fixing said plates in adjusted positions on said supports.

5. A type bar guide comprising a pair of spaced supports having guiding faces thereon, horizontally arranged plates mounted on said faces and having slots therein, screws extending through said slots into said supports for locking said plates in adjusted positions on said supports, vertically extending flanges on said plates, and horizontally extending screws engaging said flanges and threaded in said supports for adjusting said plates on said supports.

6. The combination with a typewriter platen, of a support positioned in front of

said platen, horizontally arranged plates mounted on said supports, said plates having converging guide flanges on adjacent edges thereof, threaded members for adjusting said plates in the direction of the axis of said platen independently of one another, guides for preventing angular and front and rear movements of said plates, and screws for locking said plates in adjusted positions.

7. The combination with a typewriter platen, of a pair of spaced supports positioned in front of said platen each of said supports having a horizontally and a vertically arranged flange, a plate slidably mounted on each of said horizontally arranged flanges, converging type bar guides carried by adjacent edges of said plates, screws extending through elongated slots in said plates and engaging said horizontally arranged flanges for locking said plates in position on said flanges, screws threaded in the vertically arranged flanges of said supports, and lugs on said plates engaging said last-mentioned screws to cause said plates to move in unison with said last-mentioned screws for adjusting the guiding members of said plates in the direction of the axis of said platen.

In testimony whereof I have signed my name to this specification on this 16th day of February A. D. 1922.

OTTO A. HOKANSON,
